HAND RESTJohn J. Schubert and Charles E. Ahrendt,
Evanston, Ill.

Application June 30, 1949, Serial No. 3,642

Term of patent 14 years

(Cl. D86—10)

To all whom it may concern:

Be it known that we, John J. Schubert and Charles E. Ahrendt, citizens of the United States, residing at Evanston, in the county of Cook and State of Illinois, have invented a new, original, and ornamental Design for a Combined Manicuring Tray and Hand Rest, of which the following is a specification, reference being had to the accompanying drawing, forming a part thereof.

In the drawing:

Fig. 1 is a perspective view of a manicuring tray and hand rest embodying our new design.

Fig. 2 is a top plan view of the manicuring tray and hand rest shown in Fig. 1.

Fig. 3 is a side elevational view of the manicuring tray and hand rest shown in Fig. 1.

Fig. 4 is an end elevational view taken from the left in Fig. 2.

Fig. 5 is an end elevational view taken from the right in Fig. 2.

We claim:

The ornamental design for a combined manicuring tray and hand rest, as shown.

JOHN J. SCHUBERT.

CHARLES E. AHRENDT.
